3 Claims 10

ABSTRACT OF THE DISCLOSURE

A relay having a unitary armature which is adapted 15
to be connected to a direct current source. The armature
is of a ferrous metal that is capable of being magnetized
and includes a movable end which carries a contact and
a detent spaced from and limiting movement of said end
with a direct current passing through the contact, the 20
movable end of the armature is constituted a magnetic
pole and the detent an opposite pole. Thus magnetic
properties are generated which, under certain conditions
tend to cause the movable armature end to stick to the
detent.

Background of the invention

While a relay of the type with which this invention is 30
concerned may function properly under some loads, such
as one or two lamps when the load is increased, as by
the addition of one or more lamps, the current through
the armature will increase to such an extent as to create
35 magnetism in the armature which will impair the opera-
tion of the movable contact by creating a tendency for
it to quickly part from the detent, thus interfering with
separation in the intended time. This results in destroying
the sensitivity of the frequency provided by the relay.

Summary of the invention

With this condition in mind, the invention has, as an 40
object, the provision of a relay including a current car-
rying armature and a coil having a core with the armature
and coil being related to neutralize any magnetism in
the armature when a direct current flows therethrough
in a prescribed direction.

Thus, with the movable arm of the armature consti- 50
tuted a north pole for the residual magnetism created
by the current, the current is passed through the coil in
the direction to constitute the end of the core adjacent
to the movable arm a north pole. The magnetism of the
coil is much greater than the residual magnetism in the 55
armature which it overcomes and causes the contacts to
engage and at the same time neutralizes any magnetism
which may have been created in the armature.

Various other more detailed objects and advantages of 60
the invention, such as arise in connection with carrying
out the above noted ideas in a practical embodiment, will
in part become apparent, and in part be hereinafter stated,
as the description of the invention proceeds.

For a full and more complete understanding of the
invention reference may be had to the following descrip-
tion and accompanying drawings.

Brief description of the drawing

FIG. 1 is a perspective of an obturator included in
flasher systems and is representative of the condition with
no current applied;

FIG. 2 is a perspective similar to FIG. 1 depicting
the condition which obtains when current flows through
the coil in the wrong direction;

2

FIG. 3 is still another perspective similar to FIGS. 1
and 2 illustrating the condition which is created when
the current passes through the coil in the correct direc-
tion in accordance with the precepts of this invention;

FIG. 4 is a wiring diagram of a flasher system includ-
ing the relay of this invention; and

FIG. 5 is graphic representation of the current legend
employed in this specification and defines the terms of
polarity herein used.

Description of the preferred embodiments

Referring now to the drawing, and first more particu-
larly to FIG. 5 a battery is shown at 10. A strip of con-
ducting metal is indicated at 11. This strip is comparable
of the strip constituting the armature of the relay of this
invention. A line 12 connects the positive side of the bat-
tery 10 with the end 13 of the strip 11. Another line 14
connects the negative side of the battery 10 with the end
15 of the strip 11.

With direct current flowing from the battery 10 in the
direction of the arrows appearing on lines 12 and 14 the
strip 11 is magnetized and the end 13 is the south pole
of the magnet and the end 15 the north pole.

Referring now to FIG. 1 an obturator is therein il-
lustrated and identified in its entirety by the reference
character O. It comprises an armature in the form of
an integral continuous ferrous strip comprising an end
wall 16, a base 17, a curved or arcuate end wall 18 and
a movable top piece 19. The latter extends outwardly
over the top edge 21 of end wall 16 from which it is
spaced and projecting outwardly from the movable top
piece 19 is a tongue 22. Carried on the underface of the
latter is a contact 23. The top piece 19 is formed with
an aperture 24 and passing therethrough is a narrow strip
25 which upstands from the edge 21 of front wall 16. The
strip 25 is bent over to provide a detent 26 that is posi-
tioned over the tongue 22 in narrowly spaced, substan-
tially parallel relation thereto. This spacing has been ex-
aggerated in the showings of the drawings to the end
40 of clarifying illustration.

A core 27 upstands from the base 17 and its upper
end 28 is normally spaced from the underside of the top
piece 19. A coil 29 is wound about the core 27 and in-
cluded in an appropriate circuit, such as that of a flasher,
45 as will be later described.

Referring now to FIG. 2 the condition which is cre-
ated when a direct current is passed through the coil 29
in the wrong direction will be described. A fixed con-
tact 30 is shown as spaced below the movable contact
23 with which it co-operates.

With direct current passing through the armature, as
through base 17, curved end wall 18, and top piece 19,
the latter is magnetized and the end portion thereof, in-
cluding the tongue 22 is constituted the north pole and
the detent 26 the south pole. With current passing through
the coil 29 in the direction of the arrows the core 27 is
magnetized with the end 28 becoming the south pole.
Thus top piece 19 is drawn downwardly towards the core
and the tongue 22 is correspondingly moved to bring the
contact 23 into engagement with the fixed contact 30.
However, in achieving this engagement of the contacts
the tongue 22 must be separated from the detent 26 with
the separation being resisted by the residual magnetism.

As opposite poles attract when the current is interrupted
any residual magnetism in the top piece 19 and tongue 22
is effective to tend to hold the detent and tongue together
and retard separation. It has been found that this difficulty
is not so apparent when the load of the circuit is small,
say for instance a single lamp. But when the load is in-
creased, as by adding one or more lamps to the circuit the
resulting increase in current is reflected in an increase in

the armature magnetism which causes the core to achieve the separation more quickly than in the cases of lesser current.

FIG. 3 depicts the correct direction of current flow and the condition created thereby. The only change over FIG. 2 is that current flows through the coil 29 in a direction opposite to the direction of FIG. 2. This causes the end 28 of core 27 to become a north pole.

While like poles repel the magnitude of the magnetism of coil 27 and core 29 is so great as compared to any residual magnetism in the top piece 19 the relay functions in the manner intended as described above because the residual magnetism in piece 19 is overcome. At the same time any magnetism in top piece 19 is neutralized by the magnetism of core 27.

Referring now to FIG. 4 a typical flasher circuit including the relay of this invention will be described. Thus a battery 31 is grounded at 32, as to the chassis of the vehicle in which the flasher is installed. A resistor 33 is connected to the battery 31 by a line including a control switch 34. A bus line 35 is connected to the other end of the resistor at junction 36. One side of a capacitor 37 is connected to junction 36 and a line 38 extends from the other side. The coil 29 is connected between the ends of lines 35 and 38.

A line 39 extends from the line 38 to a lamp load represented at 40. The fixed contact 30 is connected to the line 39 at 41. Another line 42 extends from the battery side of the resistor 33 to the armature to which it is connected as at 43.

From the foregoing it is apparent that if the relay is to function with the uniformity of frequency required current must pass through the coil 29 in the proper direction. As a test to determine this factor the relay is first used in a circuit with a load of say one lamp. The frequency of operation for a prescribed period is noted. A second lamp is added which increases the current. If the frequency now increases it indicates that the current is flowing in the wrong direction. If the frequency remains constant it denotes the correct direction of current flow.

Thus the present invention embraces not only the relay itself but the method by which it is tested to ensure that the coil is properly related to the armature and current flow therethrough so that any magnetism in the armature is neutralized by the coil.

While preferred specific embodiments of the invention are hereinbefore set forth it is to be clearly understood that the invention is not to be limited to the exact constructions, mechanisms and designs illustrated and described because various modifications of these details may be provided in putting the invention into practice within the purview of the appended claims.

I claim:

1. For use in a circuit providing an intermittent current of constant frequency, a unitary armature relay comprising an armature in the form of an integral strip of ferrous metal through which a direct current passes, said strip providing an end wall having an upper free edge, an extension of said wall beyond said edge and having a bent portion constituting a detent; a base integrally joined to the lower edge of said end wall; a second end wall integrally joined to said base; a movable top piece integrally joined free edge, being formed with an aperture through which said extension passes, a tongue extending from said top piece beneath said detent in operative relation thereto, a contact carried by said tongue; said direct current passing through said strip imparting magnetism thereto and opposite polarity to said tongue and detent; a core positioned between said base and top piece and having an upper end normally spaced from said top piece; and a coil disposed about said core and having a direct current passing therethrough in a direction imparting the same polarity to said core end as that which obtains in said top piece.

2. The unitary armature relay of claim 1 in which the second end wall is curved.

3. The unitary armature relay of claim 1 in which the top piece and upper core end are both north poles.
